UNITED STATES PATENT OFFICE.

ROBERT S. NOBLE, OF WEST BAY CITY, MICHIGAN.

SASH-FASTENER.

SPECIFICATION forming part of Letters Patent No. 314,974, dated March 31, 1885.

Application filed April 25, 1884. (No model.)

To all whom it may concern:

Be it known that I, ROBERT S. NOBLE, a citizen of the United States, residing at West Bay City, in the county of Bay and State of Michigan, have invented a new and useful Window-Sash Fastener, of which the following is a specification.

My invention relates to improvements in window-fasteners in which a movable cam-lever and bolt and spring operate in conjunction with rigid studs attached to a stationary plate which is firmly secured to a window-sash; and the objects of my invention are, first, to produce a window-fastener which will hold the sash firmly in any desired position; second, to afford means of leaving the sash entirely free to be moved up or down; and, third, to provide a means of securely locking automatically a window-sash when it shall be closed. I attain these objects by means of the mechanism illustrated in the accompanying drawings, in which—

Figure 1 is a front view of a portion of a sash with my invention attached thereto with the cam-lever and bolt in position for holding the sash opened. Fig. 2 is a back view of the same. Fig. 3 is a side view of the same from the edge of the sash. Fig. 4 is a front view of my invention, showing the position of the cam-lever and bolt when the sash is free to move, also the mechanism for tripping the cam to lock automatically. Fig. 5 is a back view of the same. Fig. 6 is a front view of the face-plate and studs, and showing the slot through which the screw is passed for securing the cam and lever to the bolt. Fig. 7 shows the device when the sash is locked. Fig. 8 is a back view of the same. Fig. 9 is an end view of the same opposite to that of Fig. 3. Fig. 10 is a sectional view at $x-x$ in Fig. 4.

Similar letters refer to similar parts throughout the several views.

a represents a portion of a window-sash, and b a part of the jamb of a window-easing, and c is the inside stop for holding the sash in place.

d is a plate of a suitable size, which is attached to the front side of the sash, and provided with the portions r and s , turned at right angles with the plate d , and provided with suitable holes to receive the bolt l .

e is a cam which is attached to the face-plate d by means of the screw p , which passes through the slot h in the face-plate and into the bolt l , and is firmly secured thereto. 55

f is a lever which is attached to and used to operate the cam e .

g is a stud which is attached rigidly to the face-plate d in such a position as to engage with the cam e when the lever f is moved over 6c toward the jamb.

i is a stud firmly secured to the face-plate d near the stop c , and adapted to engage with the recess t in the cam e when the lever is pressed away from the jamb. The cam e is 65 also provided near the recess t with the lug n , which, when the recess t is engaged with the stud i , is adapted to engage with the spring k , which is attached to the stop c , as shown in Fig. 4. 70

m is a spring which is coiled around a reduced portion of the bolt l , one end of the spring bearing against a shoulder on the bolt, while the opposite end bears against a portion, r , of the face-plate d , and is adapted to hold 75 the bolt l against the jamb b or into the notch v .

When the sash is open to the required position, the lever f is moved away from the jamb, which causes the cam e to engage with the stud g , and serves to press the end of the bolt 80 l firmly against the jamb b , and thereby hold the sash firmly in position, as shown in Fig. 1.

To raise or lower the sash, the lever f is moved toward the jamb and the cam is engaged with the stud i , and the bolt l moved backward and 85 there held by the stud i catching into the recess t , when the sash is free to be moved up or down, as may be seen in Fig. 4.

k is a spring-catch, the spring end of which is securely fastened to the stop c , while the other end, forming the catch, projects a short distance beyond the stop c , the face of one side of the projecting catch being at right angles with the stop c , while the opposite side or face is sloping, and for the upper sash is located 95 just below the notch v , with the sloping face of the catch above, as shown in Fig. 4.

When the bolt l is held back, as described, by the stud i catching into the recess t while the sash is being raised for closing, the projecting lug w catches upon the lower or straight side of the catch k , which serves to disengage

the recess *t* from the stud *i*, and allows the spring *m* to press the bolt *l* against the jamb *b*, and, as the sash is farther raised, the bolt *l* passes into the notch *v* in the jamb *b*, and the sash is securely locked in position.

To lower the sash, the lever *f* is drawn away from the jamb *b*, and the recess *t* is engaged with the stud *i* and holds the bolt *l* back, leaving the sash free to be moved downward, and as the under or opposite side of the lug *n* comes in contact with the upper or sloping side of the projecting catch *k* the catch *k* recedes and allows the lug *n* to pass by without disengaging the recess *t* from the stud *i*, which allows the sash to be moved freely until it reaches any desired position, when the lever *f* and cam *e* are operated and the sash secured.

What I claim, and desire to secure by Letters Patent, is—

20 1. In a window-sash fastener, the face-plate *d*, provided with the slot *h* and the studs *i* and *g*, the bolt *l*, and spring *m*, in combination with

the cam *e*, provided with the lever *f*, and secured to the bolt *l* by the screw *p* passing through the slot *h*, and adapted to engage with the stud *i* for moving the bolt *l* back and holding it free from the jamb *b* and to engage with the stud *g* for pressing the end of the bolt *l* firmly against the jamb for holding the sash in a desired position, substantially as described 25 30 and shown.

2. In an automatic sash-fastener, the plate *d*, having the studs *i* and *g* and slot *h*, the bolt *l*, provided with the spring *m*, the cam *e*, provided with the lever *f*, the recess *t*, and the projecting lug *n*, in combination with the projecting catch *k*, located and arranged to operate substantially as described, and for the purpose specified.

ROBERT S. NOBLE.
